PAPERBOARD TRAY

Lewis C. Pennebaker, Chattanooga, Tenn., assignor to O. B. Andrews Company, Chattanooga, Tenn., a corporation of Tennessee

Application June 22, 1951, Serial No. 15,640

Term of patent 14 years

(Cl. D58—14)

To all whom it may concern:

Be it known that I, Lewis C. Pennebaker, a citizen of the United States, residing at Chattanooga in the county of Hamilton and State of Tennessee, have invented a new, original, and ornamental Design for a Paperboard Tray, of which the following is a specification, reference being had to the accompanying drawing, forming a part hereof.

Fig. 1 is a side view of a paperboard tray, showing my new design.

Fig. 2 is a top view of a paperboard tray shown in Fig. 1.

Fig. 3 is an end view of a paperboard tray shown in Fig. 1.

The side of the paperboard tray not shown is substantially the same in appearance as the side illustrated.

I claim:

The ornamental design for a paperboard tray, as shown and described.

LEWIS C. PENNEBAKER.
